US0D1097876S

(12) **United States Design Patent** (10) **Patent No.:** **US D1,097,876 S**
(45) **Date of Patent:** **** Oct. 14, 2025**

(54) **DRONE**

(71) Applicant: **HANGZHOU ZERO ZERO TECHNOLOGY CO., LTD**, Hangzhou (CN)
(72) Inventor: **Bin Peng**, Zhejiang (CN)
(73) Assignee: **HANGZHOU ZERO ZERO TECHNOLOGY CO., LTD**, Hangzhou (CN)

(**) Term: **15 Years**

(21) Appl. No.: **35/521,213**

(22) Filed: **May 16, 2024**

(80) **Hague Agreement Data**

Int. Filing Date: **May 16, 2024**

Int. Reg. No.: **DM/237314**

Int. Reg. Date: **May 16, 2024**

Int. Reg. Pub. Date: **Jun. 7, 2024**

(30) **Foreign Application Priority Data**

Dec. 1, 2023 (CN) 202330792877.9

(51) **LOC (15) Cl.** **12-07**

(52) **U.S. Cl.**

USPC **D12/16.1**
